United States Patent Office

Des. 180,515
Patented June 25, 1957

180,515

COMBINED LATCH AND KEEPER

Harold E. Graves and Harold E. Graves, Jr.,
Akron, Ohio

Application July 30, 1956, Serial No. 42,453

Term of patent 14 years

(Cl. D50—5)

FIG. 1

FIG. 2

Figure 1 is a perspective view of a combined latch and keeper, showing our new design.

Figure 2 is a perspective view showing the opposed side of the combined latch and keeper.

We claim:

The ornamental design for a combined latch and keeper, as shown.
